REFRIGERATION

Alvar Lenning, Stockholm, Sweden, assignor, by
mesne assignments, to Servel, Inc., New York,
N. Y., a corporation of Delaware

Application September 14, 1936, Serial No. 100,613
In Germany November 21, 1935

19 Claims.

(Cl. 62—5)

My invention relates to refrigeration, and more particularly to control of refrigeration apparatus.

It is an object of my invention to provide an improved control device for modifying the normal operation of refrigeration apparatus, such as to initiate defrosting thereof or to instigate quick freezing, the device being operative to terminate the modified operation of the apparatus automatically.

10 Further objects and advantages of my invention will become apparent from the following description and accompanying drawings forming a part of this specification, and of which Fig. 1 diagrammatically illustrates refrigeration apparatus provided with a control device embodying my invention; Fig. 2 is an enlarged vertical sectional view of the control device shown in Fig. 1 taken on line 2—2 of Fig. 3; Fig. 3 is a sectional view taken on line 3—3 of Fig. 2 illustrating more clearly parts of the control device; Fig. 4 is a fragmentary sectional view taken on line 4—4 of Fig. 2; and Fig. 5 is a vertical sectional view of a modification of the control device shown in Fig. 2.

23 Referring to Fig. 1, I have shown my invention in connection with a refrigerator cabinet 10, only a part of which is illustrated, having thermally insulated walls 11 defining a storage compartment 12. A door (not shown) may be hinged to the front of the cabinet whereby access may be had into the storage compartment 12. A cooling element 14 of refrigeration apparatus is arranged within the storage compartment 12 for maintaining the latter at a desired low temperature. The refrigeration apparatus I have shown is of a uniform pressure absorption type which is well known in the art and in which an auxiliary pressure equalizing gas is employed. It is to be understood, however, that my invention can be employed with other types of refrigeration apparatus.

15 The refrigeration apparatus includes a generator 15 containing a refrigerant in solution in an absorption liquid, and, although I do not wish to be limited thereto, the refrigerant may be ammonia and the absorption liquid may be water. The generator 15 is provided with an upward extending pocket 16 within which is arranged an electrical heating element 17.

50 The heat applied to the generator 15 and its contents expels the ammonia out of solution, and the ammonia vapor flows upward to an air-cooled rectifier 18 which condenses any water vapor accompanying the ammonia vapor. The water condensed in the rectifier drains back to

the generator, and the ammonia vapor flows upward to an air-cooled condenser 19.

The ammonia is liquefied in the condenser 19 and flows through a conduit 20 into the upper end of an evaporator coil 21 which is arranged 5 closely adjacent to a shell and with the latter forms the cooling element 14. An inert gas, such as hydrogen, enters the upper end of the evaporator coil 21 from a vertically extending conduit 22. The hydrogen and ammonia flow in the 10 same direction in the presence of each other, and the ammonia evaporates and diffuses into the hydrogen with consequent absorption of heat from the surroundings of the cooling element. The resulting gas mixture of ammonia and hydrogen flows from the evaporator coil 21 through the outer passage 23 of a gas heat exchanger 24 and conduit 25 which communicates at its lower end with the lower end of an absorber 26 about which is arranged a coil 27 through which a cooling medium may be circulated. If desired, the absorber 26 may also be air-cooled in a manner similar to the condenser 19.

In the absorber 26 the ammonia is absorbed 25 out of the gas mixture into weak absorption liquid which enters the upper part of the absorber through a vertically extending conduit 28. The hydrogen, which is practically insoluble and weak in ammonia, passes upward from the absorber 26 through conduit 29, a plurality of parallel tubes 30 which form the inner passage of the gas heat exchanger 24, and conduit 22 to the upper end of the evaporator coil 21. The gas heat exchanger 24 transfers heat from gas weak in ammonia which is flowing to the evaporator 35 coil 21 to gas rich in ammonia which is flowing to the absorber 26. A conduit 20a extending upward from the lower end of the condenser 19 and thence downward and communicating with the outer passage 23 of the gas heat exchanger 24 is provided so that any ammonia which is not liquefied or hydrogen can flow to the gas circuit and not be trapped in the condenser. 40

The absorption liquid flowing downward through the absorber 26 in counterflow to the 45 gas mixture becomes enriched in ammonia by absorption and flows through an inner conduit 31 of a liquid heat exchanger 32 to a coil 33 disposed about the lower end of the pocket 16. The rich absorption liquid is raised by vapor-lift 50 action from the coil 33 through conduit 34 into the upper part of the generator 15. The absorption liquid is raised to a higher level in the generator 15 than it is in the absorber 26, and absorption liquid weak in ammonia flows from

the lower part of the generator through conduit 35, outer conduit 36 of the liquid heat exchanger 32 and conduit 28 into the upper part of the absorber 26.

5 In accordance with my invention the electrical heating element 17, which serves as a source of energy for the refrigeration apparatus, is controlled by a device 37 provided with a switch which is connected in series relation with the 10 heating element to a source of electrical supply indicated at 38. Referring to Figs. 2 and 3, the device 37 includes a two-part casing 39 having an upwardly extending boss 40 in the right hand part thereof to which is secured a base plate 15 41 of a mercoid switch having a removable cover 42. The mercoid switch comprises a bulb 43 containing a body of mercury 44 and having two spaced depending parts to the lower ends of which are fixed conductors 45 and 46 which are 20 connected to terminals 47 and 48 mounted on the base plate 41. The base plate 41 is provided with an opening 41a through which pass the conductors of the electrical circuit which are connected to the terminals 47 and 48. 25 The bulb 43 is mounted on a member 49 having bent ends 50 which are secured to an inverted U-shaped member 51. The member 51 is provided with openings in the side walls thereof which receive a pin 52 fixed to spaced vertical 30 brackets 53 which are mounted on the base plate 41. The inverted U-shaped member 51 and bulb 53 carried thereby rock about the pin 52, and one of the brackets 53 is provided with inwardly 35 extending projections 54 and 55 which limit the extent of rocking movement of the member 51 and bulb 43. When the right hand part of the bulb 43 is tilted downward in the position shown in Fig. 2, with the member 51 bearing against the right hand projection 55, the body of mercury 44 does not provide an electrically conductive 40 path between the conductors 45 and 46, whereby the electrical circuit is open and the heating element 17 is disconnected from the source of supply 38. When the left hand part of the bulb 43 is tilted downward with the member 51 bearing 45 against the left hand projection 54, the body of mercury 44 provides an electrically conductive path between the conductors 45 and 46, whereby the heating element 17 is connected to the source of supply 38.

In order to rock the bulb 43 about the pin 52 to connect and disconnect the heating element 17 to and from the source of supply 38, a pin 56 is secured to the side walls of the inverted U-shaped member 51 below the pin 52. The pin 56 is adapted to receive the bifurcated arms 57 formed at the upper end of a lever 58 which extends vertically downward through the boss 40 into the chamber 59 in the right hand part of the casing 39. The lower end of the lever 58 is bent back upon itself to form a double wall part having openings adapted to receive a pin 60 which is journaled in openings provided 65 in two inwardly extending projections formed in the right hand part of the casing 39. By moving the lever 58 about the pin 60 the inverted U-shaped member 51 is caused, by means of the bifurcated arms 57 and pin 56, to rock 70 about the pin 52 and move the bulb 43 to open or close the electrical circuit, as described above.

The mechanism for controlling the lever 58 and hence the position of the bulb 43 includes a short rod 61 having a rounded end 62 which fits 75 into openings formed in the spaced walls at the

lower end of the lever 58. To maintain the rounded end 62 of the rod 61 between the spaced walls at the openings formed therein the bent portion of the lever 58 and the main body portion thereof are maintained in fixed spaced relation by a screw 63, as shown in Fig. 3.

5 The rod 61 extends through an annular member 64 into a housing 65 within which is threadedly secured a sleeve 66 having a shoulder adapted to bear against a flange formed on the annular member 64. The housing 65 is closed at one end and provided with a flange at its other end to which is secured one end of an expandible bellows 67. The opposite end of the expandible bellows 67 is secured to a raised portion of a 15 plate 68.

To transmit axial movements of the bellows 67 to the rod 61 and also provide for a certain amount of play in the mechanism so that parts of the switch are not unduly strained, helical 20 springs 69 and 70 are arranged within the housing 65. The helical spring 69 is disposed about the rod 61 with the ends thereof bearing against a flange provided at one end of the rod and the flange formed on the annular member 64. The helical spring 70 is larger than the spring 69 and the ends thereof bear against the flange formed on the annular member 64 and the closed end of the housing 65. The springs 69 and 70 form a resilient connection between the rod 61 30 and bellows 67 whereby axial movements of the latter are effectively transmitted to the rod 61 and whereby any excessive movement of the bellows that may take place in either direction is taken up by the springs 69 and 70 after the 35 inverted U-shaped member 51 has contacted the stops or projections 54 and 55.

The plate 68 is provided with a threaded stud 71 which extends through an opening in the end of the casing 39. An internally threaded 40 nut 72, which is rotatable and axially immovable, is positioned at the opening at the end of the casing and receives the threaded stud 71. The nut 72 is provided with a flange 73 which bears against the inner surface of the end wall 45 of the casing, and to the portion thereof extending outside the casing is secured, as by set screws 75 and 76, a control knob 74 which bears against the outer surface of the end wall of the casing. To prevent any rotation of the plate 68 and bellows 67 when axial movement is imparted thereto by turning the control knob 74, the casing 39 is provided with a groove 77 which is adapted to receive a downward extending projection 78 formed on the plate 68, as shown most clearly in Fig. 4. The plate 68 is provided 55 with a central opening 79 which communicates with a passage formed in the stud 71 to which is connected one end of a tube 80, the other end of which is connected to a bulb 81 which is shown in thermal contact with the cooling element 14. Instead of arranging the bulb 81 in thermal contact with the cooling element 14, it may be arranged in any suitable manner to be responsive to a temperature condition affected 60 by the cooling element 14. The chamber 82 defined by the housing 65 and bellows 67, opening 79, tube 80, and bulb 81 constitute what is termed an expandible fluid thermostat which is filled with a suitable volatile fluid which increases and decreases in volume with corresponding changes in temperature.

When the cooling element 14 tends to rise above a desired low temperature the volatile fluid increases in volume and causes the bellows 75

67 to expand whereby the rod 61, through the resilient connection effected by the springs 69 and 70, is moved toward the chamber 59. Such axial movement of the rod 61 moves the lever 58 about the pin 60 and rocks the member 51 and bulb 43 carried thereby from the circuit open position shown in Fig. 2 to a circuit closing position wherein the left hand part of the bulb 43 is tilted downward. With the mercoid switch in a 10 circuit closing position, the electrical heating element is connected to the source of supply 38 whereby the generator 15 is effectively heated and cold is produced in the storage compartment 12 by the cooling element 14 to maintain the 15 latter at the desired temperature.

When the cooling element 14 tends to fall below the desired low temperature, the volatile fluid in the expansible fluid thermostat becomes reduced in volume, whereby the bellows 67 contracts to cause the rod 61 to move toward the 20 plate 68. With such axial movement of the rod 61 the bulb 43 is moved from its circuit closing position to the circuit open position shown in Fig. 2, whereby the electrical heating element 17 is disconnected from the source of supply 38 and the production of cold in the storage compartment 12 is stopped to maintain the latter at the 25 desired temperature.

The arrangement of the mechanism just described is such that with a slight movement of the rod 61 either to the left or right, a correspondingly greater movement of the lever 58 is effected at the bifurcated arms 57 to move the member 51 and bulb 43 to a position either to 30 open or complete the electrical circuit of the heating element 17. By adjusting the initial position of the control knob 74 and bellows 67 which is bodily movable, the thermostatic control will normally be effective to maintain the storage compartment 12 substantially at a desired low 35 temperature within a normal range of variations. Referring to Fig. 1, this may be accomplished by providing a plate 82' at the side of the casing 39 with the plate having a part 83 projecting forward which is in the path of movement of the upper set screw 76. The position of the set screw 76 relative to the part 83, such as the vertical position shown, for example, may be arbitrarily chosen as the position which will maintain 40 the storage compartment 12 substantially at the desired temperature within a normal range of variations.

In many instances it is desirable to modify the above described normal operation of the refrigeration apparatus, and this is particularly true when it is desired to melt frost that has accumulated on the cooling element. In order that the device 37 shall be capable of modifying the normal operation of the refrigeration apparatus to 45 permit defrosting of the cooling element 14, I provide a sleeve 84 which is arranged within the casing 39 and secured to the flange formed on the housing 65. The sleeve 84 is disposed about the bellows 67 and provided with pins or elements 85 and 86 which extend therefrom at diametrically opposite points through slots 87 and 88, respectively, which are formed at the top and bottom of the casing 39. About the casing 39 adjacent to the pins 85 and 86 is secured, as by 50 set screws 89 and 90, an annular permanent magnet or an abutment 91 having affinity in contact with the pins or elements 85 and 86 and separable by a given force value.

When it is desired to modify the normal operation of the refrigeration apparatus and permit

melting of frost on the cooling element 14, the control knob 74 that is employed to regulate and vary the normal operation is moved from the position to which it is normally adjusted to a "defrost" position whereby the bellows 67, sleeve 5 84, and pins or elements 85 and 86 are moved in a direction away from the chamber 59 and the pins or elements 85 and 86 are attracted and held by the magnet or abutment 91. With the control knob 74 in the "defrost" position 10 the bulb 43 is in the circuit open position shown in Fig. 2 and the electrical heating element 17 is disconnected from the source of supply 38. After the control knob 74 has been moved to the "defrost" position to initiate defrosting of 15 the cooling element it may be immediately returned back to its original position which determines the low temperature at which the cooling element 14 is normally maintained. However, with such return movement of the control 20 knob 74 to its original position, the pins or armature elements 85 and 86 and magnet 91 have affinity in contact and will remain attracted by the magnet 91.

Although the pins or elements 85 and 86 remain 25 attracted and held by the abutment or magnet 91, these elements remain in actuatable relation to other parts of the mechanism. During this time the bellows 67 will not be effective to move the bulb 43 to its circuit closing position with a 30 normal increase of the temperature of the cooling element 14 in the normal range of temperature variations. As the temperature of the cooling element 14 increases, the volatile fluid in the expansible fluid thermostat increases in volume. 35 When the cooling element 14 reaches an abnormally high temperature beyond the normal temperature range, which temperature is preferably above the freezing temperature of water, the pressure of the volatile fluid in the chamber 82 is sufficiently great to overcome added resistance to movement caused by the abutment or magnet 91 and force the pins 85 and 86 away from the magnet 91 to separate the abutting parts. This permits the rod 61 to move toward the chamber 59 to cause the bulb 43 to move to its circuit closing position and connect the heating element 17 to the source of supply 38 to restore normal 40 operation.

During the period of time the bulb 43 is in its 45 circuit open position and the heating element 17 is disconnected from the source of supply 38, the temperature of the cooling element 14 increases to a value above the freezing temperature of water and frost that may have accumulated on the cooling element 14 will melt and can 50 be collected in a suitable receptacle (not shown). The control mechanism is preferably adjusted so that, when the control knob 74 is moved to initiate defrosting of the cooling element 14, the latter will remain at a temperature above 55 the freezing temperature of water sufficiently long to insure substantially complete melting of frost which has accumulated on the cooling element 14. The sleeve 84 and pins 85 and 86 60 are preferably formed of soft iron, and the magnet 91 is of adequate strength so that its attractive force will be compatible with that exerted by the bellows 67.

When the pins 85 and 86 are moved away 70 from the magnet 91, the bulb 43 is immediately moved to its circuit closing position to permit heating of the generator 15 so that the temperature of the cooling element 14 decreases to 75 a value in the normal range of temperature vari-

ations. This normal range of temperature variations is determined, of course, by the position to which the control knob 74 has been returned after being moved momentarily to the "defrost" position to initiate defrosting.

After the cooling element 14 reaches the desired temperature at which it is adjusted to operate, the control device 37 will be effective to operate the mercoil switch in response to temperature changes of the cooling element 14 to maintain the latter substantially at the desired temperature in the normal range of temperature variations. During normal operation the magnet or abutment is out of reach of the pins or elements 85 and 86 which move within limitation for the normal temperature control. When frost has again accumulated on the cooling element 14 to such an extent that defrosting is desired, the control knob 74 is moved to its "defrost" position and then returned to its original position at which it is desired that normal operation will resume after the defrosting has automatically terminated.

In certain instances, particularly when it is desired to hasten the production of ice cubes in the cooling element, it is desirable to modify the operation of the refrigeration apparatus to maintain the cooling element 14 at an abnormally low temperature. In the present invention this is accomplished by providing the sleeve 84 with two additional pins or elements 92 and 93 which also extend through the slots 87 and 88, respectively, at the top and bottom of the casing. When it is desired to modify the normal operation of the refrigeration apparatus to maintain the cooling element 14 at an abnormally low temperature the control knob 74 is moved to a "quick freezing" position whereby the bellows 67 and sleeve 84 are moved toward the chamber 59 and the pins 92 and 93 are attracted and held by the magnet 91. After the control knob 74 has been moved to the "quick freezing" position, it may be immediately returned to its original position which determines the low temperature at which the cooling element 14 is normally maintained. With such return movement of the control knob 74 to its original position, however, the pins 92 and 93 having affinity in contact with the magnet 91 remain attracted by the magnet 91, and the bellows 67 assumes such a position that the bulb 43 remains in its circuit closing position. With the pins 92 and 93 held by the magnet 91, the bellows 67 will not be effective to move the bulb 43 to its circuit open position with a normal decrease of the temperature of the cooling element 14. As the temperature of the cooling element 14 decreases, the volatile fluid in the expansible fluid thermostat becomes reduced in volume. When the cooling element 14 reaches an abnormally low temperature, which temperature is preferably below the freezing temperature of water, the contracting force of the expansible bellows 67 becomes sufficiently great to overcome added resistance to movement caused by the abutment or magnet 91 and force the pins 92 and 93 away from the magnet 91 to cause the bulb 43 to move to its circuit open position and disconnect the heating element 17 from the source of supply 38.

During the period of time the pins 92 and 93 are attracted and held by the magnet 91, the bulb 43 remains in its circuit closed position, thereby permitting the temperature of the cooling element 14 to decrease. In this instance the control mechanism is preferably adjusted so

that, when the control knob 74 is moved to instigate "quick freezing," the cooling element will reach a temperature below the freezing temperature of water to insure complete freezing of water in trays which have been placed in the cooling element.

When the pins 92 and 93 are moved away from the magnet 91 by the force of the bellows 67 due to contraction thereof, as described above, the bulb 43 is immediately moved to its circuit open position to disconnect the heating element 17 from the source of supply 38 so that the temperature of the cooling element 14 will increase to a value in the normal range of temperature variations. This normal range of temperature variations is determined by the position to which the control knob 74 has been returned after being momentarily moved to instigate quick freezing. After the cooling element 14 reaches the normal operating temperature, the device 37 will be operative to control the mercoil switch in response to temperature changes of the cooling element 14 to maintain the latter substantially at the desired temperature in the normal range of temperature variations.

In Fig. 5 I have shown a modification of my invention which is similar to the embodiment just described and differs therefrom in that the control device 37' is arranged to control the flow of gas to a burner 94. The burner 94 is arranged to project its flame into the lower end of a flue 95 which extends upward through the generator 15' and about which a vapor-lift coil 33', similar to the vapor-lift coil 33 in Fig. 1, is arranged.

A suitable combustible gas is delivered from a source of supply through conduit 96, control device 37', and conduit 97 to the burner 94. A bypass conduit 98 is provided around the control device 37' to maintain a pilot flame at the burner 94 when the supply of gas to the latter is shut off.

The control device 37' comprises a two-part casing 39' having bosses 99 and 100 in the right hand part thereof which form inlet and outlet openings, respectively, for the combustible gas. The gas flows from the inlet opening at the boss 99 into diaphragm chamber 59', and from the latter through a port 101 into a valve chamber 102 which communicates with the outlet in the boss 100.

The port 101 forms a valve seat which is adapted to cooperate with a valve 103 having a hollow stem 104. Between a shoulder formed on the stem 104 and a short sleeve 105 threadedly secured to the stem is fixed a resilient diaphragm 106. The peripheral edge of the diaphragm 106 is secured between a shoulder formed on the inside of the casing 39' and a plate 107 having an opening through which the sleeve 105 extends and in which it is guided. The resilient diaphragm 106 is provided to make diaphragm chamber 59' gas-tight so that the flow of gas from this chamber to the outlet opening at the boss 100 is insured.

The valve 103 is urged or biased toward its closed or seated position by a helical spring 108 disposed within the valve chamber 102. The valve 103 is urged to its open position against the tension of the spring 108 by means including a rod 61' which extends into the hollow stem 102. The rod 61' is enlarged at one end and threadedly secured within a housing 65. The housing 65 and other parts of the control device 37' are similar to the control device 37 described above and are referred to by similar reference

numerals, so that a description thereof will not needlessly be repeated here.

When the cooling element 14 tends to rise above the desired temperature the expansible fluid thermostat causes the bellows 67 to expand and move the valve 103 to the right against the tension of the helical spring 108 to increase the flow of gas to the burner 94; and conversely, when the cooling element 14 tends to fall below the desired temperature, the expansible fluid thermostat permits the bellows 67 to contract and allow the valve 103 to be urged toward its closed position to decrease the flow of gas to the burner 94. By adjusting the initial position of the control knob 74 and hence the position of the bellows 67, the thermostatic control will normally be effective to maintain the storage compartment 12 substantially at a desired temperature in a normal range of temperature variations.

In order to modify the operation of the refrigeration apparatus to initiate defrosting of the cooling element 14 or to instigate quick freezing, the operation of the control device 37' is similar to that described above in connection with the control device 37 shown in Fig. 2. When the control knob 74 is momentarily moved to the "defrost" position and subsequently moved back to its original position, the bellows 67 and rod 61' will not be effective to open the valve 103 with a normal increase of the temperature of the cooling element 14. As the temperature of the cooling element 14 increases the volatile fluid in the expansible fluid thermostat increases in volume. When the cooling element 14 reaches an abnormally high temperature beyond the normal temperature range, which temperature preferably is above the freezing temperature of water, the pressure of the volatile fluid in the chamber 82 is sufficiently great to overcome added resistance to movement caused by the abutment or magnet 91 and force the pins 85 and 86 away from the magnet 91, whereby the rod 61' is moved toward the right so as to contact valve 103 and open the latter.

During the period of time the bellows 67 is contracted and the rod 61' does not positively control the valve 103, the supply of gas to the burner 94 is reduced, thereby decreasing the heating of the generator 15' and permitting the temperature of the cooling element 14 to increase. When the temperature of the cooling element 14 increases to a value above the freezing temperature of water, frost that may have accumulated on the cooling element 14 will melt and can be collected in any suitable manner. When the pins 85 and 86 are moved away from the magnet 91, as described above, the valve 103 is immediately moved to an open position to permit heating of the generator 15' so that the temperature of the cooling element 14 will decrease to a value in the normal operating range of the apparatus.

When it is desired to maintain the cooling element 14 at an abnormally low temperature the control knob 74 is momentarily moved to the "quick freezing" position and subsequently returned to its original position which determines the low temperature at which the cooling element 14 is normally maintained. With such return movement of the control knob 74 to its original position, however, the pins 92 and 93 remain attracted by the magnet 91 and the bellows 67 assumes such a position that the rod 61' maintains the valve 103 open against the tension of the spring 108. With the pins 92 and

93 held by the magnet 91 the bellows 67 will not be effective to move the rod 61' toward the left and permit the valve 103 to move toward its closed position with a normal decrease of the temperature of the cooling element 14. As the temperature of the cooling element 14 decreases the volatile fluid in the expansible fluid thermostat becomes reduced in volume. When the cooling element 14 reaches an abnormally low temperature beyond the normal temperature range, which temperature is preferably below the freezing temperature of water, the contracting force of the bellows 67 becomes sufficiently great to overcome added resistance to movement caused by the abutment or magnet 91 and force the pins 92 and 93 away from the magnet 91, whereby the rod 61' is moved toward the left to permit the valve 103 to move to its closed position due to the tension of the spring 108.

During the period of time the pins 92 and 93 are held by the magnet 91 and the bellows 67 does not positively control the valve 103, the supply of gas to the burner 94 is increased, thereby increasing the heating of the generator 15' and permitting the temperature of the cooling element 14 to decrease. When the temperature of the cooling element 14 decreases to a value below the freezing temperature of water, the water is completely frozen.

When the pins 92 and 93 are moved away from the magnet 91 by the contracting force of the bellows 67, as described above, the rod 61' is moved toward the left and the valve 103 is immediately moved toward its closed position to reduce the supply of gas to the burner 94 so that the temperature of the cooling element 14 will increase to a value in the normal range of temperature variations. This normal range of temperature variations is determined, as mentioned above, by the position to which the control knob 74 is moved after being moved momentarily to initiate quick freezing.

In view of the foregoing it will be understood that I have provided an improved control device for refrigeration apparatus which is operative either to initiate defrosting or instigate quick freezing, the device being automatically operative to terminate such defrosting or quick freezing. Although I have shown several embodiments of my improved control device in connection with a particular type of refrigeration apparatus, I do not wish to be limited to the particular arrangements set forth, and I intend in the following claims to cover all modifications which do not depart from the spirit and scope of my invention.

What is claimed is:

1. In refrigeration apparatus including a cooling element, a source of energy for said apparatus, control means including a part normally responsive to a temperature condition affected by said cooling element to control said source of energy, a magnet, an armature element carried by said part, said magnet and armature element normally being spaced apart, and means for causing said armature element to be attracted and held by said magnet to modify the control of said source of energy and permit said cooling element to reach an abnormal value of temperature, said control means being automatically operative when said cooling element reaches an abnormal value of temperature to force said armature element away from said magnet so that said control means is operative to resume the normal control of said source of energy.

2. In refrigeration apparatus including a cooling element, a source of energy for said apparatus, control means including a thermal element normally responsive to a temperature condition affected by said cooling element for controlling said source of energy, a magnet, an armature element carried by said thermal element, said magnet and said armature element normally being spaced apart, and means for bodily moving said thermal element to cause said armature to be attracted and held by said magnet to modify the control of said source of energy and permit said cooling element to increase to an abnormally high temperature, said thermal element being capable of expanding when said cooling element increases to an abnormally high temperature to force said armature element away from said magnet so that said control means is operative to resume the normal control of said source of energy.

3. In refrigeration apparatus including a cooling element, a source of energy for said apparatus, control means including a thermal element normally responsive to a temperature condition affected by said cooling element for controlling said source of energy, a magnet, an armature element carried by said thermal element, said magnet and said armature element normally being spaced apart, and means for bodily moving said thermal element to cause said armature element to be attracted and held by said magnet to modify the normal control of said source of energy and permit said cooling element to decrease to an abnormally low temperature, said thermal element being capable of contracting when said cooling element reaches an abnormally low temperature to force said armature element away from said magnet so that said control means is operative to resume the normal control of said source of energy.

4. In refrigeration apparatus, a control member, a thermal element to normally operate said control member, means including a part manually movable to adjust the operation of said control member effected by said thermal element, a magnet, and an armature normally spaced from said magnet and movable with said thermal element, and means including said part to cause said armature to be attracted and held by said magnet to modify the normal operation of said control member.

5. In refrigeration apparatus, a control member, a thermal element to normally operate said control member, a magnet, and an armature normally spaced from said magnet and movable with said thermal element, and means to cause said armature to be attracted and held by said magnet to modify the normal operation of said control member by said thermal element, said thermal element being automatically operative upon a predetermined change of temperature to force said armature away from said magnet whereby said thermal element is operative to resume normal operation of said control member.

6. In a regulator for refrigeration apparatus including a control member and mechanism responsive to temperature of a body to be cooled within a normal range of variations to operate said control member, structure including an element movable responsive to such temperature variations within limitation for such normal temperature control, an abutment, and means to move said element into contact with said abutment, said abutment being disposed out of reach of said element in normal operation, said

abutment and element having affinity in contact and separable by a given force value, said structure being so constructed and arranged that said element remains in actuatable relation to other parts of said mechanism when contacting said abutment, whereby temperature beyond normal range is effective to overcome added resistance to movement caused by such abutment and separate the abutting parts to restore normal operation upon predetermined variation of temperature from normal.

7. In a regulator for refrigeration apparatus including a control member and mechanism responsive to temperature of a body to be cooled within a normal range of variations to operate said control member, structure including an element movable responsive to such temperature variations within limitation for such normal temperature control, an abutment, and means to move said element into contact with said abutment, said abutment being disposed out of reach of said element in normal operation, said abutment and element being magnetically attractive to each other when in contact and separable by a given force value, said structure being so constructed and arranged that said element remains in actuatable relation to other parts of said mechanism when contacting said abutment, whereby temperature beyond normal range is effective to overcome added resistance to movement caused by such magnetic attraction and separate the abutting parts to restore normal operation upon predetermined variation of temperature from normal.

8. In refrigeration apparatus having a control element and mechanism for normally operating the control element responsive to temperature in a normal range of variations, structure including a first member, a second member movable relative to said first member and normally out of reach of said first member during normal operation of the control element, said members being magnetically attractive, means to cause said second member to move toward said first member so that said members are magnetically held together, said members being separable by a given force value when magnetically held together, and said structure being so constructed and arranged that said second member is in actuatable relation to said mechanism when said members are magnetically held together, whereby temperature beyond normal range is effective to overcome added resistance to movement caused by the magnetic attraction of said members and separate said members to restore normal operation of the control element upon predetermined variation of temperature from normal.

9. In refrigeration apparatus having a control element and mechanism for normally operating the control element responsive to temperature in a normal range of variations, structure including a first member, a second member movable with said mechanism, said second member being out of reach of said first member during normal operation of the control element, common means to adjust said mechanism to raise or lower the normal temperature range and to move said second member into abutting relation with said first member, said members having affinity in contact and separable by a given force value, said structure being so constructed and arranged that said second member remains in actuatable relation to said mechanism when contacting said first member, whereby temperature beyond

5 normal range is effective to overcome added resistance to movement caused by such abutment and separate said abutting members to restore normal operation of the control element upon predetermined variation of temperature from normal.

10. In refrigeration apparatus having a cooling element and mechanism responsive to a temperature condition affected by the cooling element for normally controlling the apparatus to keep the temperature condition in a normal range, structure including a first member, a second member movable with respect to said first member, said second member being out of reach of said first member during normal control of the apparatus by the mechanism, and means to cause said second member to bear against said first member, said members having affinity to remain held together when said second member bears against said first member, and said structure being so constructed and arranged that said second member is operatively associated with the mechanism when bearing against said first member, whereby resistance to normal movement is effected to modify the control of the apparatus and cause an abnormal change in the temperature condition from the normal range.

11. In refrigeration apparatus having a cooling element and mechanism responsive to a temperature condition affected by the cooling element for normally controlling the apparatus to keep the temperature condition in a normal range, structure including two magnetically attractive members out of magnetic attraction during normal control of the apparatus by the mechanism, and means to cause one member to move toward another member so that said members are magnetically held together, said structure being so constructed and arranged that said one member is operatively associated with the mechanism when said members are magnetically held together, whereby resistance to normal movement is effected to modify the control of the apparatus and cause an abnormal change in the temperature condition from the normal range.

12. In refrigeration apparatus having a control device and mechanism including an expandable and contractible thermal element for normally operating the device responsive to temperature in a normal range of variations, structure including a first member movable with the thermal element, a second member out of reach of said first member during normal operation of the device by the mechanism, means to move said first member into contact with said second member, and said structure being so formed and constructed that said members have sufficient affinity when in contact to produce resistance to normal movement of the thermal element to modify the normal operation of the device by the mechanism and cause an abnormal change in temperature from the normal range.

13. In refrigeration apparatus having a control device and mechanism including an expandable and contractible thermal element for normally operating the device responsive to temperature in a normal range of variations, structure including two magnetically attractive members out of magnetic attraction during normal operation of the device by the mechanism, one of said members being operatively connected to the thermal element and movable therewith, means to cause the one member to move toward

the other member so that said members are magnetically held together, and said structure being so constructed and arranged that said members when magnetically held together will produce resistance to normal movement of the thermal element to modify the normal operation of the device by the mechanism and cause an abnormal change in temperature from the normal range. 5

14. In refrigeration apparatus having a control device and means including an expandable and contractible thermal element for normally operating the control device responsive to temperature in a normal range of variations, said thermal element being bodily movable, structure 10 including a first member movable with said thermal element, a second member normally out of reach of said first member, said members having affinity to remain held together when said first member bears against said second member and 20 operative to modify the normal operation of the control device when bearing against each other, means to bodily move said thermal element to cause said first member to bear against said second member, and said structure being so constructed and arranged that said first member will be forced away from and out of reach of said second member to restore normal operation 25 of the control device responsive to force produced by the thermal element upon variation of 30 temperature beyond the normal range.

15. In refrigeration apparatus having a control device and means including an expandable and contractible thermal element for normally operating the control device responsive to temperature in a normal range of variations, said thermal element being bodily movable, structure 35 including a first member movable with said thermal element and a second member normally out of reach of said first member, said members being magnetically attractive to each other and operative to modify the normal operation of the control device when said first member is moved toward said second member so that said members are magnetically held together due to the 40 magnetic field therebetween, means to bodily move said thermal element to cause said members to be held together magnetically, and said structure being so constructed and arranged that said first member will be forced away from and 45 out of reach of said second member to restore normal operation of the control device responsive to force produced by said thermal element upon variation of temperature beyond the normal range. 50

16. In refrigeration apparatus including a cooling element and control means for normally keeping the cooling element in a normal temperature range, structure including two magnetically attractive members normally spaced apart during normal control and operatively associated with the control means to determine an abnormal temperature beyond the normal range when caused to move toward each other so that said members are held together due to 65 the magnetic field therebetween, and means to bring said members together so that they will be magnetically attracted to each other. 55

17. In refrigeration apparatus including a cooling element and control means for normally 70 keeping the cooling element in a normal temperature range, structure including two magnetically attractive members normally spaced apart during normal control and operatively associated with the control means to determine 75

- an abnormal temperature beyond the normal range when caused to move toward each other so that said members are held together due to the magnetic field therebetween, and means including a single operating element for adjusting the control means to raise or lower the normal temperature range and for bringing said members together so that they will be magnetically attracted to each other.
18. In refrigeration apparatus provided with a cooling member and control means for normally keeping the cooling member in a normal temperature range, modifying means operatively associated with the control means for modifying the normal control whereby the cooling member is reduced to an abnormally low temperature below the normal temperature range, said modifying means normally being inoperative, and means including a single control member for adjusting the control means to raise or lower the normal temperature range and for rendering said modifying means operative to modify

the normal control effected by said control means.

19. In refrigeration apparatus provided with a cooling member and thermostatic control means for normally keeping the cooling element in a normal temperature range, modifying means operatively associated with the thermostatic control means for modifying the normal control whereby the cooling element is reduced to an abnormally low temperature below the normal temperature range, said modifying means normally being inoperative, and means including a single control member for adjusting the thermostatic control means to raise or lower the normal temperature range and for rendering said modifying means operative to modify the normal control, said thermostatic control means being operative when the cooling member reaches an abnormally low temperature to render said modifying means inoperative so that normal control is effected by the thermostatic control means.

ALVAR LENNING.
